UNITED STATES PATENT OFFICE.

MARCUS FALK, OF HARTFORD, CONNECTICUT.

STEP-LADDER.

SPECIFICATION forming part of Letters Patent No. 729,561, dated June 2, 1903.

Application filed November 6, 1902. Serial No. 130,230. (No model.)

To all whom it may concern:

Be it known that I, MARCUS FALK, a citizen of the United States, residing in the city of Hartford, in the county of Hartford and State of Connecticut, have invented new and useful Improvements in Step-Ladders; and I do hereby declare the following to be a full, clear, and exact description of the invention, such as will enable others skilled in the art to which it appertains to make and use the same.

This present invention relates to step-ladders composed of interdependent and coöperating parts arranged substantially as shown in the accompanying drawings, in which—

15 Figure 1 shows a step-ladder in perspective constructed in accordance with my invention. Fig. 2 shows in elevation a portion of a step-ladder incorporating my invention. Fig. 3 is a detail view of one of the extensible legs of my step-ladder detached. Fig. 4 is a detail view shewing a portion of the top surface of one of the treads with the extensible leg and a portion of the frame in section, and Fig. 5 is a detail view of one of the 25 castings.

Similar indices refer to and denote like parts throughout the several views.

The object of this invention is to provide a step-ladder with auxiliary extensible legs on the front supports, whereby the ladder may be adjusted to stand level even when the front legs are placed on a lower surface than the rear legs—as, for instance, stairways or the like.

35 Another object is to provide a step-ladder adapted to stand level on a level surface and also adjustable to stand level on two different elevations, which will be simple in character, compact in form and construction, easily operated, and whereby the operator will be enabled to perform his work with safety and in a minimum of time and with a saving of labor.

Another object is the provision of an article of manufacture—an adjustable step-ladder—which can be manufactured and sold at a comparatively low price.

45 Other objects and advantages will appear from the following specification and from the drawings forming a part thereof.

50 Referring now to the drawings, A and B represent the rear leg members of a step-ladder united by cross bars and braces in any

well-known manner. C represents the top or platform, extending down from the under side of which near each end are cross-blocks 55 C' and C'', to the rear portions of which are pivoted the upper ends of the said legs A and B.

D represents spreaders adapted to hold the legs A and B at the desired point when extended.

E represents a shelf.

All of the above-named parts are old and may be variously changed to suit the various requirements.

Extending downward and forward at an angle from the cross-blocks C' and C'', respectively, are the front-leg members 1 and 2, provided with slots 3 and 4, respectively, extending from the lower ends upward to almost the 70 upper ends thereof, as shown.

5 represents castings, formed substantially as shown in Fig. 5, provided with openings 5' therethrough for the purpose hereinafter appearing.

6 represents a plurality of treads or steps extending across between the legs 1 and 2 at frequent distances apart.

Each of the legs 1 and 2 is provided with a number of castings 5, secured therein, as shown in Fig. 4, the portion forming the opening 5' projecting through the slots 3 and 4 and the free ends being adapted to grip the ends of the treads 6. Said castings 5 are secured to the legs 1 and 2 by screws or nails which pass 85 through the legs, the castings, and project into the ends of the treads 6, as shown in Fig. 4, thus securing the castings in place in the legs and also securing the ends of the treads in place in the castings. The treads 6 are 90 further secured by nails or screws passing through the parallel ends of the castings and into the front and rear edges of the treads 6, as shown. After all the castings 5 and treads 6 are secured in place, as shown, it will be 95 seen that the two rows of castings 5 will provide guideways by means of the openings 5', extending from the top to the bottom of the legs 1 and 2. I now provide two auxiliary legs 7 and 8 of a length substantially the same 100 as the length of the slots 3 and 4 and of a size to loosely fit into the openings 5'. The lower ends of the legs 7 are forked, and secured in the forks are blocks 8 and 8, one edge

of which is adapted to rest level on the floor of a room, and secured on the under edge of the block 8 are rubbers 9 to prevent the ends of the legs from slipping. It will now be apparent that the legs 7 may be inserted in the openings 5', as shown in Figs. 1 and 4, or they may be extended to the point desired, as shown in Fig. 2.

The indices α represent openings passing through the legs 1 and 2 at right angles thereto and through the slots 3 and 4, and α represents openings passing through the legs 7, adapted to be brought into alinement with the openings α at various points.

15 10 and 10 represent two bolts or pins adapted to pass through the openings α and α , by which the legs 7 may be secured at the extended point desired.

It will now be seen that my step-ladder may 20 be placed on a level floor and used in the usual manner, as shown in Fig. 1; but should it be desired to use my ladder, for instance, on a stairway the rear legs A and B may be placed on an upper step and the legs 7 may 25 be extended to reach a much lower step in order to keep the treads 6 on a level, and the legs 7 may then be secured at that point by means of the bolts 10, as shown.

My invention is perfectly adapted to accomplish the purposes for which it is intended, and it is evident that changes in and modifications of the specific construction herein shown and described may be made and that analogous parts may be used to accomplish 30 the same results without departing from the spirit of my invention or sacrificing any of its many advantages, and the specific construction of the details of my invention may be variously changed without altering the essential principles which are claimed as new.

Having now fully shown and described my invention and the best mode for its construction and use to me known at this time, what I claim as new, and desire to secure by Letters Patent of the United States, is—

1. In an extensible step-ladder the combination, of the two forward legs each provided with a slot extending from their lower ends to near the upper ends, a plurality of castings 5 secured at frequent distances apart in each 50 of said slots, said castings forming projecting ends into which are secured the ends of the treads, and each of said castings having an opening 5' forming guides for the auxiliary legs, of the auxiliary legs adapted to slide in 55 said openings in the castings 5 and parallel with the legs 1 and 2, a block 8 secured in the lower ends of the legs 7, and a rubber secured on the lower face of said blocks, all substantially as shown and described and for the purposes set forth.

2. In a step-ladder the combination of the main supporting-legs 1 and 2 formed with a slot extending from the bottom to near the top thereof, of the castings 5 secured in said 60 slots at frequent distances apart, the tread secured in said castings the auxiliary legs 7 adapted to be adjusted endwise through openings in the castings 5, means for securing the legs 7 at various points along the lengths 70 thereof, and a contact-block and rubber secured on the lower ends of each of the legs 7, substantially as shown and described.

In testimony whereof I have hereunto signed my name to this specification in the 75 presence of two subscribing witnesses.

MARCUS FALK.
